Primary Examiner — Khawaja Anwar*Assistant Examiner* — Mojtaba Tehrani(74) *Attorney, Agent, or Firm* — Mathieu Audet(57) **CLAIM**

The ornamental design for a quiver, as shown and described.

DESCRIPTION

FIG. 1 is a top-rear isometric view of a quiver, showing my new design;

FIG. 2 is a bottom-rear isometric view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof; and,

FIG. 8 is a back elevation view thereof.

The broken lines in the drawings depict unclaimed portion of the quiver only and form no part of the claimed design.

1 Claim, 8 Drawing Sheets(56)
